UNITED STATES PATENT OFFICE.

MARK J. LIDDELL, OF SOUTH ENGLEWOOD, ILLINOIS.

STOVE-PIPE DRUM.

SPECIFICATION forming part of Letters Patent No. 391,541, dated October 23, 1883.

Application filed December 5, 1887. Serial No. 257,041. (No model.)

To all whom it may concern:

Be it known that I, MARK J. LIDDELL, of South Englewood, in the county of Cook and State of Illinois, have invented a new and Improved Stove-Pipe Drum, of which the following is a full, clear, and exact description.

My invention relates to a drum for receiving and radiating heat from products of combustion passing through a draft-pipe leading from a stove or heater, with a view to economy of fuel consumed in heating one or more apartments; and the invention has for its object to provide a simple, inexpensive, and efficient device of this character.

15 The invention consists in certain novel features of construction and combinations of parts of the stove-pipe drum, all as hereinafter described and claimed.

Reference is to be had to the accompanying drawings, forming a part of this specification, in which similar letters of reference indicate corresponding parts in all the figures.

Figure 1 is a central vertical section of my improved stove-pipe drum and parts of connected joints of pipe. Fig. 2 is a plan view of the drum in horizontal section on the line *x*, *x*, Fig. 1.

The outer wall or cylinder, *A*, of the stove-pipe drum is made in two parts or sections—30 an upper part, *A'*, and a lower part, *A''*—which are fitted together, preferably near the lower end of the cylinder, which is inclined or tapers to a short pipe or neck, *a*, to which a joint, *B*, of stove-pipe is adapted, while the 35 tapering upper end of the cylinder has fitted to it an inner direct-draft flue or pipe, *C*, to the projecting end *c* of which the upper joint, *D*, of stove-pipe is fitted. The inner pipe, *C*, extends for quite a distance through the drum, 40 and is directly in line with a shorter pipe, *E*, which is fitted into the bottom *f* of the intermediate wall or cylinder, *F*, of the drum and in line with the neck *a* of the outer cylinder. The pipes *C* and the neck *a* are separated to 45 give passage to heated products of combustion, in a manner presently explained. A lower damper, *E'*, fitted in the pipe *E*, is provided with a stem, *e'*, which extends through the side of the drum to allow operation of the 50 damper.

I show the inner cylinder, *F*, made in two parts; but it may be made in one piece, if

preferred. This cylinder or cylindrical cup *F* is supported within the main outer cylinder, *A*, and above its bottom or lower end, by feet 55 or brackets *G*, fixed to it and to the end of the main cylinder or wall of the stove-drum, and in a manner to provide a space or passage, *H*, between the margin of the bottom *f* of the cylinder *F*, and hold the sides of the cylinder 60 about midway between the outer wall, *A*, and inner pipe, *C*, of the drum, thereby providing a passage or flue, *I*, between the cylinders *A* and *F* and a passage or flue, *J*, between the cylinder *F* and the inner pipes, *C* and *E*. 65

On the pipe *C* there is fitted a short pipe or collar, *K*, to which is connected one end of a rod, *L*, the lower end of which is preferably forked at *l* to embrace the collar *K*, and the upper part of the rod *L* passes upward through 70 the end of the outer cylinder, *A*, into position to allow it to be grasped for conveniently sliding the collar *K* on the pipe *C*, so as to open the space at *e* between the adjacent ends of the pipes *C* and *E*, as shown in full lines in Fig. 1 of 75 the drawings, or to close said space *e*, as indicated by the dotted lines.

In the upper-end or neck, *c*, of the pipe *C* is fitted a damper consisting of two semicircular plates, *M* and *M'*, each of which is pivoted at its 80 inner edge by a pin, *m*, to the pipe.

The operation of the stove-drum is as follows: When the collar or damper *K* is raised on the pipe *C* to open the space *e* between the pipes *C* and *E* and the lower damper, *E'*, is closed, as 85 shown in full lines in the drawings, all the products of combustion passing from a stove or heater to which the pipe *B* is connected will enter the drum-neck *a*, and will pass outward through the passage *H* and upward into the 90 flue *I*, and thence downward through the flue *J* and through the opening *e* into the pipe *C*, and thence upward past the open damper *M* and *M'* into the pipe *D*, and thence to the draft-flue, to which this pipe is connected. With this 95 adjustment of the dampers in cold weather a lively circulation of the hot products of combustion will be allowed and maintained in direct contact with the wall of the outer cylinder, *A*, and within the inner cylinder, *F*, and 100 a large amount of heat which would otherwise escape to the draft-flue is retained, and then given off or radiated by the main cylinder *A* to the room, and fuel is economized.

It is obvious when the collar-damper K is lowered to close the opening e between the pipes C E, and as indicated by the dotted lines in Fig. 1 of the drawings, and when the damper 5 E' is open, that the heated products from the stove cannot have free circulation through the passage H and flues I J, and a practically direct draft of the products of combustion from the stove or heater will be maintained through 10 the drum-neck a and the pipes E C D to the draft-flue. The outer wall or cylinder, A, will then give off very little heat to the room in which the stove or its draft-pipe is placed, as required in warm or moderately-cool weather, 15 and while the heat is thus practically cut off from the outer main heat-radiating cylinder, A, a direct draft is allowed through the drum to the chimney-flue.

By making the main cylinder A of the drum 20 in separable parts the whole interior of the drum is made easily accessible for cleaning or repairs.

It is obvious that the two pipes C E may 25 be made as one pipe provided with one or more slots or openings at e, which may be closed by the sliding damper K on the pipe; but the two pipes give a larger opening at e, and are therefore preferred in practice.

Having thus described my invention, what I 30 claim as new, and desire to secure by Letters Patent, is—

1. A stove-drum made with an outer cylinder, an intermediate cylinder, and an inner

draft-pipe, providing draft-flues I J, said draft-pipe provided at or near its lower end with an 35 opening, e, and a damper on the draft-pipe controlling said opening, substantially as herein set forth.

2. A stove-drum made with an interior draft-flue comprising pipes C E, separated 40 from each other at adjacent ends, and a collar or damper, K, fitted to the pipes and adapted to close the opening e between them, substantially as described, for the purposes set forth.

3. The combination, in a stove-drum, of an 45 outer cylinder, an intermediate cylinder, and an inner draft-pipe provided at or near its lower end with an opening, e, a damper fitted on the draft-pipe to control said opening, and a damper fitted in the draft-pipe below said 50 opening, substantially as described, for the purposes set forth.

4. The combination, in a stove-drum, of an outer cylinder, A, an intermediate cylinder, F, having a bottom, f, and supported by 55 brackets G from the bottom of the cylinder A, an interior draft-pipe, C E, providing an opening at e, a collar or damper, K, fitted to this pipe and adapted to close the opening e, and a damper, E', fitted to the interior draft-pipe 60 below the opening e, substantially as described, for the purposes set forth.

MARK J. LIDDELL.
